Patented Feb. 20, 1917.

Inventor

Job Dudley

By J. E. Dudley, Atty.

UNITED STATES PATENT OFFICE.

JOB DUDLEY, OF HAMILTON, ONTARIO, CANADA.

HACKSAW-MACHINE.

1,216,669.

Specification of Letters Patent. Patented Feb. 20, 1917.

Application filed May 18, 1916. Serial No. 98,371.

To all whom it may concern:

Be it known that I, Job DUDLEY, a subject of the King of Great Britain, residing at Hamilton, in the county of Wentworth and 5 Province of Ontario, Canada, have invented a new and useful Hacksaw-Machine, of which the following is a specification.

My invention relates to improvements in hacksaw machines for cutting or severing 10 metal bars, pipes and the like, and in which two horizontally-reciprocating saw-blade arms operate in unison with each other and in the same vertical plane, upon the metal bar by means of novelly constructed mechanism 15 in connection with a drive wheel.

The objects of my invention are, first, to provide an apparatus for effectively severing bars of hard metal in a substantial reduction of the time which was hitherto required 20 to accomplish that work, second, to provide a machine of this character which is durable and accurate in its work, third, to provide means whereby two saw-blade arms can be operated simultaneously, one cutting 25 upward and the other cutting downward, and fourth, to afford means whereby a continuous cutting motion is attained.

I attain these objects by the mechanism illustrated in the accompanying drawing, in 30 which:—

Figure 1 is a side elevation of the entire machine, showing the mechanism in operating position:

Fig. 2 is an enlarged detail view of the 35 balance arm hub with the nearest bearing and integral guide removed in order to more clearly illustrate the method of automatically locking said arm:

Fig. 3 is a rear detail view through the 40 line 3—3: in Fig. 1 of the drawing, and

Fig. 4 is an enlarged detail top view of the rear slotted member, the rear blade arm guides, and a portion of the blade arms.

Similar characters of reference refer to 45 similar parts throughout the several views.

The table B, the post C, and the legs D and E, constitute the framework of the machine.

The metal bar or pipe 2 which is to be 50 cut, is inserted between the jaws 3 and 4 of a vise, the jaw 3 of which is rigidly secured to the table B by means of a bolt 5, but may be longitudinally adjusted to a desired position by the manipulation of said bolt.

When the bar 2, which may be of any reasonable size, is placed in position, the jaw 4 is tightened against it by means of the screw 6 which threads through the upper end part of the post C. A suitable handle 7 is fixed to the opposite end of the screw 6 for turning purposes.

The above parts are not new, and do not form part of my invention.

9 and 10 are saw-blade arms provided with integral arched forward end portions 65 11 and 12 respectively, and a saw-blade 13 is rigidly secured to respective heads on either end of each said integral arched portion.

The saw-blade arms 9 and 10 are adapted 70 to reciprocate simultaneously, the saw-blades meeting each other as the metal bar is cut through. The said arms are operated by means of the mechanism now to be described.

An oscillatory lever 14 is fulcrumed at its central point to a rigid bearing 15 on the table B, its upper end part being pivotally connected to a shaft 16, the opposite end of which shaft is pivotally connected to a drive 80 wheel 17 at a point between its center and its perimeter.

The drive wheel 17 is suitably and substantially journaled in a rigid bearing on the rear end part of the table, and is adapted 85 to rotate by means of any suitable power.

The upper end part of the lever 14 is also pivotally connected to a link 19, the opposite end of which link is connected in the same manner to an integral projection on 90 the saw-blade arm 9, and a similar link 20 is connected in like manner, to the lower end part of the lever 14 and to a similar integral projection on the saw-blade arm 10.

It can be seen that the rotation of the 95 wheel 17 will cause the saw-blade arms 9 and 10 to reciprocally oscillate by means of the above described mechanism.

21 are parallel perpendicular members rigidly secured to the rear end part of the 100 table B, and provided with parallel horizontal slots 22. The rear end parts of the arms 9 and 10 are adapted to slide between said members 21, and are retained at a uniform distance apart by means of bolts 23 105 which pass through the same, their ends protruding in the said slots.

It may be said that the length of the slots

22, and the distance traversed by the end parts of the lever 14 when the same is oscillating, are equal.

It will be seen that in order to acquire a clean and true cut on the metal bar 2, the respective saw-blades 13 must work in the same vertical plane. This is accomplished by means of vertical guides 24 and 25. The guide 24 is rigidly secured by means of bolts, 10 at its lower end part to the face of the table B, and at its upper end part to a vertical bracket 26 which is rigidly secured by means of bolts to the said table flush with the side thereof, as shown in Fig. 3 of the 15 drawing. The said guide 24 is retained at substantially the same distance from the side of the table B and bracket 26 as the width of the saw-blade arms 9 and 10, by means of a bushing 27 around the bolt at its upper end part, and at its lower end part by a balance arm hub 29 hereinafter to be described.

The arrangement of the guide 25 is similar to that of the guide 24, excepting for its 25 lower end part which is retained from the table by means of a bushing around a bolt 30.

The lower saw-blade arm 10 is tensioned against the material which is being cut, 30 by means of a balance lever 31, which is pivoted at its central hub 29 to a bearing 32 on the lower end part of the guide 24. The said bearing is also the heretofore described means for securing the lower end 35 part of the guide 24 to the face of the table B.

The said balance lever is provided with an integral rounded front end part 33 adapted to engage with the integral arched portion 12 of the saw-blade arm 10 as shown. The opposite and rear end of said balance lever is provided with a counter weight 34 which is considerably heavier than the saw-blade arm 10. It can be seen that by this 45 means, the said saw-blade arm is always tensioned against the material which is being cut.

When the material is cut through, the two saw-blade arms will naturally contact with 50 each other, and the weight of the upper arm 9 combined with that of the lower arm 10, resisting the counter weight 34, will bring said arms to a point lower than that of actual commencement of work. This act automatically locks the balance lever 31, in the manner to be described, in order that there 55 may be no pressure when the machine is not in use.

A vertically slidable latch 35 fits loosely 60 between the guide 24 and the face of the table B, its ends protruding through vertically disposed guide slots 36 in the said guide and table. The hub 29 is provided with a notch 37 which is substantially 65 the same width as the slots 36. When

the balance lever 31 is tilted as when the machine is operating, the latch 35 rests upon the circumference of the hub 29, but when the cutting operation is finished, and the weight of the saw-blade arms 9 and 10 causes 70 the balance lever 31 to level, the notch 37 in the hub 29 arrives flush with the slots 36 allowing the latch 35 to descend into the said notch, thereby effectively locking said balance lever. 75

As illustrated in the drawing, the respective saw-blades 13 are set slightly in from the faces of the arms 9 and 10, in order that they may not touch one another when the said arms contact. 80

Having fully described my invention, what I claim and desire to secure by Letters Patent, is:—

1. In a hacksaw machine of the character described, a table, a rear projecting member secured to said table and provided with parallel horizontal slots, horizontally disposed saw-blade arms adapted to reciprocally oscillate in one vertical plane, means on the rear ends of said arms adapted to engage with said slots, and means on said table to oscillate said arms, substantially, and for the purpose specified. 85

2. In a hacksaw machine of the character described, a frame, a horizontally disposed saw-blade arm adapted to oscillate in said frame and to operate downward by means of its own weight, a similar saw-blade arm adapted to reciprocally oscillate with the aforesaid arm and to operate upwardly in the same vertical plane therewith, means for oscillating said arms, a balance lever fulcrumed to the frame, a counter weight secured to one end of said lever, an integral rounded portion on the opposite end of said lever and tensioned against the upwardly acting saw-blade arm, and means for automatically locking said lever when the machine is not operating. 95

3. In a hacksaw machine of the character described, the combination of a frame and table, vertically disposed guide arms rigidly secured to said frame, horizontal saw-blade arms adapted to reciprocally oscillate in one vertical plane and between said 110 guide arms, a rear projecting member secured to said table and provided with parallel horizontal slots, means on the rear ends of said saw-blade arms adapted to engage with said slots, and means on said table to oscillate said arms, substantially, and for the purpose specified. 115

4. In a hacksaw machine of the character described, the combination of a frame and table, vertically disposed, front, and lateral guides rigidly secured to said frame in alinement, horizontal saw-blade arms adapted to reciprocally oscillate in one vertical plane determined by said guides, a rear projecting member secured to said table and 125 120 125 130

provided with horizontal slots, means on the rear ends of said saw-blade arms adapted to engage with said slots, means on the table to oscillate said arms, and a balance lever fulcrumed to the frame and tensioned upwardly against the upwardly acting arm, substantially as set forth.

In witness whereof, I have hereunto affixed my signature at Hamilton, Ontario, Canada.

JOB DUDLEY.
